UNITED STATES PATENT OFFICE.

DAVID H. GUTMAN, OF PHILADELPHIA, PENNSYLVANIA.

DESIGN FOR A VELOCIPED.

42,916.

Specification for Design.

Patented Aug. 20, 1912.

Application filed June 4, 1912. Serial No. 701,668. Term of patent 7 years.

To all whom it may concern:

Be it known that I, DAVID H. GUTMAN, a citizen of the United States, residing in Philadelphia, Pennsylvania, have invented a new, original, and ornamental Design for Velocipedes, of which the following is a specification.

My design for a velocipede is shown in the accompanying drawing, which represents a perspective view of a velocipede embodying the design.

I claim:

The ornamental design for a velocipede, as shown.

In testimony whereof, I have signed my name to this specification, in the presence of two subscribing witnesses.

DAVID H. GUTMAN.

Witnesses:

KATE A. BEADLE,
HAMILTON D. TURNER.
